[57] ABSTRACT

Pulse Width Modulator, an electrical circuit device to modulate width of electrical square shaped pulses under influence of magnetic field, said device comprising two saturable magnetic cores, each core surrounded by windings, each winding having diode in series and both said core-windings-diodes elements banded or surrounded firmly by control elements, whereby supplied square shaped pulses on windings with diodes are transferred to consumption circuit distorted into parts substantially independent from original.

PULSE WIDTH MODULATOR, AN ELECTRICAL CIRCUIT DEVICE TO MODULATE WIDTH OF ELECTRICAL SQUARE SHAPED PULSES

This invention, a Pulse Width Modulator, generates positive pulses, negative pulses or alternate polarity pulses. Pulse width is controlled by microampere range D.C. current(s) in one or indefinite number of control circuits. Control circuit(s) may be electrically isolated from each other as well as from consumption circuit(s). The generated pulse power, supplied to the consumption circuit has amplification value many thousands to many millions times greater than that of control power.

This invention improves the application of high speed power transistors in circuits which use pulses on the transistor base whose width is controlled by D.C. signal(s). The Pulse Width Modulator simplifies electronic circuits because the number of otherwise necessary active and passive components is reduced drastically. Consequently, this invention decreases total product weight, reduces production costs and improves reliability.

This Pulse Width Modulator offers flexibility in application because any signal polarity can provide to the consumption circuit positive (+) or negative (-) polarity output pulses which can be in the form of two terminal output, three terminal center tap output, or two isolated outputs each having two terminals. It can be used in other fields besides power circuit applications. For instance, it is applicable for switching and amplification and differential amplification with sensors in pollution control instrumentation. Successful use of this invention can be made in electronic circuits generating mathematical functions such as addition, subtraction, multiplication, division, squaring and square root extraction. Exhibits marked FIGS. 4 to 17 inclusive show how flexible this invention is by appropriate interconnection of the Pulse Width Modulator to power supply and consumption circuits.

The present known pulse width modulator designs are complicated and crowded with many active and passive electronic components and performance is restricted to one input-output mode. Most of the present known pulse width modulators require more control power than supplied output pulse power to the consumption circuit. Another disadvantage of most present known pulse width modulators is poor signal isolation from output pulses.

The object of this invention is to provide an electronics component which would improve present control circuits in the following ways:

1. Increase reliability of circuits.
2. Decrease quantity of active and passive components.
3. Decrease weight of the total product.
4. Decrease size of circuits.
5. Offer fast frequency response.

These objectives are achieved by the following characteristics of this invention:

1. Electrical pulse width modulation where pulse repetition rate is in kilohertz (KHz) to megahertz (MHz) range, depending on particular design and materials used.
2. Pulse width is controlled by either D.C. current or D.C. voltage.
3. High gain pulse power amplification.

4. The output(s) on consumption circuit(s) is controlled by indefinite number of input or control circuits.

5. The control circuit(s) is electrically isolated from the output circuit(s).

6. All control circuits are electrically isolated with respect to each other.

7. Flexibility in output pulse mode is achieved because different output pulse modes can be obtained from any polarity control current.

8. Pulse width is controllable by control circuits(s) from zero width, which represents zero output on consumption circuit, to approximately 95 percent of the duration as determined by the repetition rate.

9. Indefinite number of output pulse patterns are obtainable.

A general description of the exhibits marked FIGS.

1 through 17 is as follows:

FIG. 1 is a basic illustration of the invention called Pulse Width Modulator used in conjunction with a square wave power supply. Only one power winding W is shown in this figure for each core, however an indefinite number of power windings with diode in series can be applied.

FIG. 2 is the B-H loop characteristic pertinent to the core material used in the Pulse Width Modulator. This figure also demonstrates the physical concept and theory of performance of this invention described in detail in Conditions No. 1 through No. 4 following the general description of FIGS. 3 through 17.

In the following descriptions of FIGS. 3 through 17:

Outputs E_{3-4-5} and E_{6-7-8} , generated from power supply B, are equal with respect to magnitude and polarity.

Output E_{3-4-5} is electrically isolated from output E_{6-7-8} . Reference characters are defined as follows:

P.W.M.—Pulse Width Modulator.

A_1, A_2 —Saturable magnetic cores.

B—Square wave power supply.

B_a —Wave shape form from terminal 4 to 3 and from terminal 7 to 6 of the square wave power supply.

B_b —Wave shape form from terminal 4 to 5 and from terminal 7 to 8 of the square wave power supply.

C—D.C. voltage source.

D_1, D_2 —Diodes.

P—Pulse characteristic on consumption circuit R_L .

P_1 —Pulse characteristic on consumption circuit R_{L1} .

P_2 —Pulse characteristic on consumption circuit R_{L2} .

R_L, R_{L1}, R_{L2} —Consumption circuits or loads.

R_1, R_2 —Current limiting resistors.

1,2,3 . . . 2n—Terminal numbers.

FIG. 3 represents the cancelling effect of induced electromagnetic forces in control circuit(s). This figure is used in the later explanation of the amplification phenomenon of the Pulse Width Modulator.

FIGS. 4 through 17 show seven output pulse patterns, irrespective of signal polarity, when each core has one power winding with diode in series. By placing two power windings with diodes in series on each core 28 additional basic output pulse patterns are obtained. If the number of power windings are increased to an indefinite number, an indefinite number of pulse patterns are obtainable.

FIG. 4 is P.W.M. interconnection with power supply B for positive signal current and positive output pulses P appearing on load R_L .

FIG. 5 is P.W.M. interconnection with power supply B for negative signal current and positive output pulses P appearing on load R_L .

FIG. 6 is P.W.M. interconnection with power supply B for positive signal current and negative output pulses P appearing on load R_L .

FIG. 7 is P.W.M. interconnection with power supply B for negative signal current and negative output pulses P appearing on load R_L .

FIG. 8 is P.W.M. interconnection with power supply B for positive signal current and positive output pulses P_1 and P_2 alternately appearing on two loads R_{L1} and R_{L2} respectively with common return, previously referred to as three terminal center tap output.

FIG. 9 is P.W.M. interconnection with power supply B for negative signal current and positive output pulses P_1 and P_2 alternately appearing on two loads R_{L1} and R_{L2} respectively with common return.

FIG. 10 is P.W.M. interconnection with power supply B for positive signal current and negative output pulses P_1 and P_2 alternately appearing on two loads R_{L1} and R_{L2} respectively with common return.

FIG. 11 is P.W.M. interconnection with power supply B for negative signal current and negative output pulses P_1 and P_2 alternately appearing on two loads R_{L1} and R_{L2} respectively with common return.

FIG. 12 is P.W.M. interconnection with power supply B for positive signal current and alternate polarity pulses P appearing on load R_L .

FIG. 13 is P.W.M. interconnection with power supply B for negative signal current and alternate polarity pulses P appearing on load R_L .

FIG. 14 is P.W.M. interconnection with power supply B for positive signal current and positive output pulses P_1 and P_2 alternately appearing on two loads R_{L1} and R_{L2} respectively, each load having separate return.

FIG. 15 is P.W.M. interconnection with power supply B for negative signal current and positive output pulses P_1 and P_2 alternately appearing on two loads R_{L1} and R_{L2} respectively, each load having separate return.

FIG. 16 is P.W.M. interconnection with power supply B for positive signal current and negative output pulses P_1 and P_2 alternately appearing on two loads R_{L1} and R_{L2} respectively, each load having separate return.

FIG. 17 is P.W.M. interconnection for negative signal current and negative output pulses P_1 and P_2 alternately appearing on two loads R_{L1} and R_{L2} respectively, each load having separate return.

The mechanical and electrical description of this invention is detailed as follows:

The P.W.M. consists of two saturable magnetic cores (FIG. 1), Core A_1 and Core A_2 , each core characterized by high frequency capability. FIG. 1 shows Core A_1 with a winding designated by symbol W_1 and Core A_2 with another winding designated by W_2 called power windings. An indefinite number of power windings can be wound on Core A_1 and Core A_2 and each power winding has one diode in series. Terminals 1 and 2 designate W_1 on Core A_1 with Diode D_1 in series, and terminals 3 and 4 designate W_2 on Core A_2 with Diode D_2 in series. Core A_1 and Core A_2 with windings W_1 and W_2 respectively are assembled one on top of the other. Then an indefinite number of windings, herewith called control windings, are wound on this two-core (Core A_1 and Core A_2) assembly. Terminals 1 and 3 have equal polarities on diodes and windings. Terminals 2 and 4

have equal winding polarities but opposite winding polarities with respect to terminals 1 and 3.

An alternate method of assembly consists of winding W_1 on Core A_1 with diode in series, and then an indefinite number of control windings are wound on the Core A_1 assembly, and similarly Core A_2 has winding W_2 and diode in series, and then an indefinite number of control windings are wound on the Core A_2 assembly. The control windings from Core A_1 assembly and Core A_2 assembly are then interconnected in pairs in the polarities relationship which would produce an equivalent effect as described for the two core-winding-diode assemblies assembled one on top of the other. An indefinite number of power windings can be applied to the above described core-winding-diode assembly.

An indefinite number of control windings can be added to the assembly. The number of possible winding terminals has the formula $(2n-1), 2n$. Terminal $(2n-1)$ is an odd numbered terminal and $2n$ is an even numbered terminal, where n is equal to or larger than 3. Terminals 1, 3, 5, 7 . . . $(2n-1)$ have equal polarities to each other, but have opposite polarities to terminals 2, 4, 6, 8 . . . $2n$.

The theory of the Pulse Width Modulator is as follows:

CONDITION No. 1: This condition is characterized by FIG. 1. In this state power supply B is not connected to the P.W.M., and all control windings are open. FIG. 2 shows that the operating point on the B-H loop of each magnetic core is at positive reminiscence point BR_1 for Core A_1 and at BR_2 for Core A_2 .

CONDITION No. 2: This condition represents physical state characterized by FIG. 4, except that all control windings are open. When the positive half cycle Ba of power supply B delivers positive volt-seconds to terminal 1, point BR_1 on B-H loop of Core A_1 proceeds toward point SAT_3 shown in FIG. 2. This change exercises almost zero volt-seconds swing in Core A_1 , because the magnetic core is in its saturated state as seen in FIG. 2. The supplied positive volt-seconds on terminal 1 of the P.W.M. senses only winding D.C. resistance and almost all pulse power of full duration is delivered on consumption circuit R_L . During this time the negative half cycle Bb of the power supply B delivers negative volt-seconds to terminal 3 of the P.W.M. as shown in FIG. 4. However, current to the winding and to the consumption circuit R_L is blocked by Diode D_2 . During the next half cycle terminal 1 of the P.W.M. receives negative half cycle volt-seconds and current is blocked from the consumption circuit R_L by Diode D_1 . Therefore, operating point on the B-H loop (FIG. 2) of Core A_1 returns from point SAT_3 to its reminiscence point BR_1 . In this second half cycle terminal 3 of the P.W.M. receives positive volt-seconds, and consequently, operation point BR_2 proceeds toward point SAT_4 because the change occurs on the saturated part of the B-H loop of Core A_2 and because Diode D_2 does not block positive volt-seconds.

Since D.C. resistance of W_2 is small in comparison to D.C. resistance of consumption circuit R_L , consumption circuit receives almost all power in positive square pulses of full duration. The next cycle repeats the above described process.

CONDITION No. 3: This condition is similar to Condition No. 2, with the addition of one control circuit, terminals 7 and 8 and D.C. voltage source C as shown in FIG. 4. D.C. voltage source C generates bias current

which is limited by resistance R_2 and is adjusted to that magnitude and polarity which produces $(-)$ Hc oersteds in the magnetic cores. Consequently, the reminiscence point BR_1 (FIG. 2) proceeds to point B_1 for Core A_1 and reminiscence point BR_2 proceeds to point B_2 for Core A_2 . Now when power supply B delivers alternate positive and negative volt-seconds to terminal 1 and terminal 3 , point B_1 proceeds toward point SAT_1 and point B_2 proceeds toward point SAT_2 in Core A_1 and Core A_2 respectively. In this condition (Condition No. 3) there occurs a swing of magnetic lines in the quantity of one half of total volt-seconds. One half of the delivered volt-seconds is absorbed by Core A_1 and Core A_2 and the remaining volt-seconds are delivered to the consumption circuit in positive square power pulses of one-half width of full duration. The theory is explained as follows: 1) Supplied volt-seconds from power supply B are constant in area and in amplitude during pulse repetition time. 2) Supplied voltseconds from power supply B , during pulse repetition time, are equal in quantity to the maximum volt-seconds which can be absorbed by Core A_1 and Core A_2 with their respective windings W_1 and W_2 . 3) One half of delivered volt-seconds from power supply B is consumed by Core A_1 and W_1 during the swing on the B-H loop from point B_1 to point A_1 , and from point B_2 to point A_2 for Core A_2 as shown in FIG. 2. The remaining one half of supplied volt-seconds are delivered to consumption circuit during the continued swing on the saturated part of the B-H loop from Point A_1 to point SAT_1 and from point A_2 to point SAT_2 for respective Cores A_1 and A_2 with windings W_1 and W_2 .

CONDITION No. 4: This condition is similar to Condition No. 3 supplemented by the introduction of one additional control circuit, terminals 5 and 6 , as shown in FIG. 4. A signal current is supplied through a limiting resistor R_1 to terminal 5 , terminal 6 being either grounded or floating. When signal current is in the magnitude and polarity which produces $(+)$ Hc oersteds on the B-H loop, then point B_1 proceeds toward point BR_1 for Core A_1 and point B_2 proceeds toward point BR_2 for Core A_2 . Consequently, consumption circuit receives power pulses of full duration. The opposite case occurs when signal current produces $(-)$ Hc oersteds. In that case point B_1 would proceed toward point C_1 for Core A_1 and point B_2 would proceed toward point C_2 for Core A_2 as shown in FIG. 2. A condition of zero output exists because consumption circuit receives no volt-seconds. This state can be called "cut-off" condition. This condition exists because all supplied volt-seconds from power supply B are consumed by the volt-seconds swing in Core A_1 with winding W_1 during the first pulse time of full duration and consumed by Core A_2 with winding W_2 during the following pulse time of full duration. This is true until supplied volt-seconds from the power supply B are equal or less than volt-seconds capacity of Core A_1 and Core A_2 , with windings W_1 and W_2 respectively. "Full-on" time or "time of full duration" is approximately 95% of the time determined by the pulse repetition rate. This repetition rate is set up in power supply and in Core A_1 and Core A_2 design together with power windings design, and can vary from microsecond to milisecond range.

There is an indefinite number of states between "full-on" state and "cut-off" state, and any pulse width is obtainable within this range depending on the magnitude

and polarity of signal current. This is true for all other control circuits and is not restricted to terminals 5 and 6 . Moreover, all control circuits can be used at one time, whereby "net" effect of adding and subtracting will appear on the pulse width delivered to the consumption circuit.

The above described theory of operation is explanatory to all pulse width modes presented in the exhibits marked FIG. 4 to FIG. 17 inclusive.

In this invention control power is in microwatt or fraction of microwatt range and pulse power on consumption circuit is in watt(s) range. This means there is power amplification in addition to the function of pulse width control. This amplification exists because electromagnetic forces (EMF), equal in magnitude but opposite in direction are induced in the control windings, thereby cancelling each other and leaving control power to overcome control circuit D.C. resistance and to generate appropriate control current magnitude.

For a better understanding of the physical phenomenon of power amplification it is assumed that P.W.M. is at the state described under Condition No. 3. During positive volt-seconds supply on terminal 1 the volt-seconds swing takes place in Core A_1 , in the following way:

$$B_1 - - - A_1 - - - SAT_1$$

Due to this change in Core A_1 assembly an electromagnetic force, EMF_1 , is induced in the control winding $5,6$ (FIG. 3). At the same time terminal 3 of Core A_2 is supplied by negative volt-seconds and current flow on terminal 3 is blocked by Diode D_2 .

However, during the time of previous pulse duration Core A_2 was supplied with positive volt-seconds, and consequently, the operating point proceeded to point SAT_2 . While volt-seconds swing $B_1 - - - A_1 - - - SAT_1$ takes place in Core A_1 , another volt-seconds swing takes place in Core A_2 due to reset current in bias winding, terminals 7 and 8 , in the following way:

$$SAT_2 - - - BR_2 - - - B_2$$

Due to this change in Core A_2 another electromagnetic force, EMF_2 , is induced in the control windings $5,6$.

These reactive forces, EMF_1 and EMF_2 , are coincident in time and are equal in magnitude because of equal volt-seconds swing but are opposite in direction and thereby cancel each other. Cancellation of the reactive forces EMF_1 and EMF_2 in control winding $5,6$ leaves control current or control power in the magnitude of magnetization current to supply the necessary oersteds (Hc) to shift points B_1 and B_2 for wider or narrower volt-seconds swing on the consumption circuit(s). In other control windings $7,8 \dots (2n-1)$, $2n$ cancellation of induced electromagnetic forces, in principle, is the same as that described above. However, magnitude of these electromagnetic forces can be different and therefore in winding $7,8$ (FIG. 3) are designated as EMF_3 and EMF_4 .

What is claimed as new and useful to be secured by Letters-Patent of the United States is:

1. Electrical pulse width modulating device comprising at least two saturable magnetic cores; at least two diodes; electrical conductive wire;

said elements assembled to comprise a device which has first input means consisting of at least two terminals to receive alternate polarity power pulses from external power supply and second input

means consisting of at least two terminals to receive d.c. as well as variable frequency signals and output means consisting of at least two terminals for transferring current flow to the consumption circuit means;

said elements assembled as follows: at least two saturable magnetic cores, each core having conductive winding means, herein called power winding means, wrapped around each core resulting in two terminals for each power winding and at least two terminals for each core, each said power winding having a diode coupled in series and in proper polarity in respect to the polarity of power winding to permit current flow in one direction in power winding means; each power winding-diode arrangement serving as first input means and as output means where one said terminal coupled to external power supply means, called first input means, receives alternate polarity power pulses and the opposite terminal, called output means, transfers width modulated power pulses to consumption circuit means; said cores, power windings, and diodes combined into an assembly having at least two terminals which serve as first input means and at least two terminals which serve as output means; the signal

5
